(57) **CLAIM**

The ornamental design for an insulin reminder device as shown and described.

DESCRIPTION

FIG. 1 is a perspective view of an insulin reminder device showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

The ornamental design which is claimed is shown in solid lines in the drawings. The broken lines shown in the figures represent portions of the device that form no part of the claimed design.

1 Claim, 4 Drawing Sheets(56)
